Primary Examiner — Leanne Was-Englehart*(74) Attorney, Agent, or Firm* — Berenato & White, LLC**CLAIM**

The ornamental design for a door lite, as shown and described.

DESCRIPTION

FIG. 1 is a front elevational view of a door lite, with the rear view being a mirror image thereof;

FIG. 2 is a left side elevational view, with the right side being a mirror image; and,

FIG. 3 is a top view, with the bottom view being a mirror image.

Broken lines representing boundary lines are unclaimed subject matter that do not form part of the claimed design.
